UNITED STATES PATENT OFFICE

EDGAR W. REUTENER, OF BAY VILLAGE, OHIO, ASSIGNOR TO THE WM. A. HOWE COMPANY, OF CLEVELAND, OHIO, A CORPORATION OF OHIO

HINGE-TAPE-AFFIXING MACHINE

Application filed August 15, 1928. Serial No. 299,781.

This invention relates generally to a machine or apparatus for affixing tape to display signs or cards whereby to form a hinge to permit the sign to be folded along predetermined lines.

With the large size display signs which are usually made of cardboard or some similar material, it is necessary to provide means for permitting the signs to be folded so as to 10 make an attractive display and to enable the sign to be supported in an upright position. In such signs, it has been customary to score or cut the cardboard along predetermined lines so that the same may be folded. Unless 15 some means are provided for reinforcing the cardboard adjacent this scored or cut portion, the sign will frequently become broken at the fold. I have therefore provided a machine for affixing tape or a strip of flexible 20 material over the scored portion to provide a hinge which will permit the sign to be folded many times without breaking. These signs are made in a variety of sizes and shapes and 25 signs of different types or sizes are not folded along the same lines. It is therefore the main object of this invention to provide a machine for affixing tape to signs which can be adjusted for use on signs of different types or 30 sizes so as to form a hinge at any desired point.

Another object of the invention is to provide an apparatus of the character described which is simple and compact in construction, efficient and dependable in operation, readily 35 assembled and disassembled and well adapted for production at comparatively low cost.

Further and more limited objects of the invention will appear as the description proceeds and by reference to the accompanying 40 drawing in which Fig. 1 is a view in end elevation of the right hand or drive end of the machine; Fig. 2 is a view in end elevation of the left hand end of the machine; Figs. 3 and 4 are fragmentary detail views of the sign 45 showing the tape affixed thereto so as to provide a hinge; Fig. 5 is a fragmentary front elevation of the machine taken on the line 5-5 of Fig. 2 with the feeding table omitted; Fig. 6 is a vertical cross sectional view of the 50 machine taken on the line 6-6 of Fig. 5; and

Fig. 7 is a plan sectional view of the machine taken on the line 7-7 shown in Figs. 2, 5 and 6.

Referring now to the drawings the reference character 1 designates generally the frame or support having a base 2, upright members 3 and 4, and cross pieces 5. Carried by the frame is a feed table 6 and a discharge table 7. Journaled on the frame at one side thereof are upper and lower feed shafts 8 and 9. Keyed on the shaft 8 are a plurality of feed rollers 10 and keyed on the shaft 9 are a plurality of feed rollers 11. Journaled on the frame at the opposite side thereof are upper and lower feed shafts 12 and 13 on which are keyed a plurality of feed rollers 14 and 15, respectively. Journaled in the frame above the table 6 and adjacent the shaft 8 is a shaft 16 on which is keyed a pair of rolls 17 and 17^a which are slidable along the shaft, 70 the purpose of which will hereinafter appear. Extending transversely of the frame are a pair of stationary shafts 18 and 18^a. Carried by the shafts 18, 18^a are a pair of platforms or shelves 19 which are slidable along the 75 shafts transversely of the frame. Resiliently and adjustably mounted on one of the platforms 19 is a stub shaft 20 carrying a roller 21 which is urged into engagement with the roller 17 by coil springs 22 and 22^a. A similar 80 roller 21^a is carried by the other platform 19 and is urged into engagement with the roller 17^a by coil springs 23 and 23^a. The lower rollers 11 and 15 project through suitable openings provided in the table 6 and are 85 spaced from the upper rollers 10 and 14 a distance slightly less than the thickness of the display signs. The upper and lower rollers are driven in opposite directions as indicated by the arrows in Fig. 6 and serve to grip 90 the signs and to move the same across the table 6. The reference character A in Fig. 6 designates one of the signs about to be gripped by the feed rollers.

Extending transversely of the frame above 95 the table 6 are a pair of stationary shafts 24, 25. Carried by the shafts 24 and 25 are a pair of platforms or shelves 26 and 27 which are slidable along the shafts independent of each other. The platform 26 is shown in section 100

in Fig. 6 and supported on the platform 26 is an adhesive container 28. Journaled in the platform 26 is a shaft 29 on which is keyed a paste roller 30. Also journaled on the platform 26 is a shaft 31 on which is keyed a feed roller 32. The shaft 31 is adjustably mounted and may be moved toward or away from the shaft 29 by means of adjusting screws 33. The roller 30 dips into the adhesive container 28 and is driven in the direction indicated by the arrow in Fig. 6. The feed roller 32 is driven in the opposite direction and normally bears against the roller 30. Keyed on the shaft 31 is a gear 34 which meshes with a gear 35 keyed on shaft 29. Carried by the platform 26 is a substantially rectangular frame in which are journaled rollers or pulleys 36, 37, 38, 39, 40, 41 and 42. Rotatably mounted in this frame is a roll of tape or similar flexible material 43. The free end of the tape is passed over roller 36, thence under roller 37, then across roller 30, thence under roller 38 and under roller 39, thence upwardly over roller 40, thence across and over roller 41, thence downwardly over roller 42 and thence around the roller 17^a. As the tape is passed over the paste roll 30 it will be coated with a layer of adhesive material. The end of the tape will be affixed to the display sign being fed across the feed table 6 by the feed rolls 10 and 11. The roller 21^a which is resiliently mounted and urged against the roller 17^a by the springs 23 and 23^a provides sufficient pressure to cause the tape to be affixed to the sign. It should be pointed out that the signs are first scored or cut along straight lines and are fed between the rollers 17^a and 21^a in such a position that the tape is affixed to the sign immediately over the scored portion. The platform 26 and the mechanism carried thereby may be moved along the shafts 24 and 25 transversely of the frame and is secured in the desired position by clamping screws 24^a and 25^a. The lower platform 19 may also be moved along the shafts 18 and 18^a and is secured in the adjusted position by clamping screws 18^b. The roller 17^a is also adjustable along the shaft 16 to properly position the same with respect to the adhesive applying mechanism. The platform 27 is likewise adjustable transversely of the frame along the shafts 24 and 25 and is secured in the adjusted position by clamping screws 24^b and 25^b. The platform 27 likewise is provided with mechanism for applying adhesive to the tape which is identical with the mechanism described in connection with the platform 26, the corresponding parts being designated by the same reference character with the exponent "a". Supported on the top of the frame is an electric motor M by means of which the apparatus is driven although it is understood that the drive may be modified as desired. According to the preferred embodiment of my invention,

the motor M drives a shaft 44 through a suitable reduction gearing or transmission 45. Keyed on shaft 45 is a sprocket 46 which drives sprocket 47 keyed on shaft 16 through a chain 47^a. Keyed on the opposite end of shaft 16 is a gear 48 which drives a gear 49 loosely mounted on shaft 8. Shaft 8 is driven from shaft 16 through sprocket 48^a, sprocket 49^a and chain 50^a. Upper feed shaft 12 is driven from shaft 16 through sprocket 50, chain 51 and sprocket 52. Lower feed shaft 13 is driven from shaft 16 through gear 48, loosely mounted gear 49, sprocket 53 which is non-rotatably connected with gear 49, sprocket 54 and chain 55. Lower feed shaft 9 is driven from lower feed shaft 13 through sprocket 54^a, chain 55^a and sprocket 56 keyed on the opposite end of shaft 9. It will therefore be seen that shafts 8, 12 and 16 are driven in the same direction and that shafts 9 and 13 are driven in the same direction but opposite to the shafts 8, 12 and 16. 70 75 80 85

Keyed on shaft 16 intermediate the ends thereof are gears 56 and 57 which serve to drive the adhesive applying mechanisms carried by the platforms 26 and 27 respectively. The gears 56 and 57 are freely slidable along the shaft 16. Gear 56 drives a gear 58 keyed on shaft 31 through chain 59. Gear 57 drives a gear 58^a keyed on shaft 31^a through a chain 59^a. 90 95

The operation of the apparatus is as follows: The display signs are first cut or scored along straight lines about which they are to be folded and are placed on the feed table 100 face down and fed between the feed rolls 10 and 11 which grip the same on opposite sides and feed them across the table between the rolls 17 and 21 and 17^a and 21^a. The tape with the adhesive applied to one side thereof is fed in strips between the rolls 17 and 21 and the rolls 17^a and 21^a where the coated side of the tape is applied to the display signs immediately over the scored portions. The signs are usually scored so as to be folded along two straight lines. They are fed across the table and engaged between the rear feed rolls 13 and 14 and delivered onto the discharge table. The tape applying mechanisms are adjustable transversely along the frame 105 independent of each other to adapt the device for use with different signs and types of signs in which the folds are in different places with respect to the signs. It will now be clear that I have provided an apparatus which will accomplish the objects of the invention as hereinbefore stated. Various changes may be made in the details of construction and arrangement of parts without departing from the spirit of my invention and my invention is 110 115 120 125 to be limited only in accordance with the scope of the appended claims.

Having thus described my invention, what I claim is:—

1. A machine of the character described 130

- comprising a frame, a feed table carried by said frame, feed rolls for moving display signs across said table longitudinally thereof, a pair of shafts carried by said frame, a plurality of platforms supported on said shafts and movable along said shafts transversely of said feed table, a tape affixing roller journaled in said frame, mechanism carried by each of said platforms for supporting a roll of hinge tape and for unwinding the tape from the roll and feeding the same to said tape affixing roller and including means for applying an adhesive to one side of the tape as it is being unwound.
- 15 2. A machine of the character described comprising a frame, a feed table carried by said frame, means for moving display signs across said table longitudinally thereof, a pair of shafts carried by said frame, a plurality of platforms supported on said shafts and movable along said shafts transversely of said feed table, a tape affixing roller journaled in said frame, mechanism carried by each of said platforms for supporting a roll of hinged tape and for unwinding the tape from the roll and feeding the same to said tape affixing rollers and including means for applying an adhesive to the tape as it is being unwound.
- 20 3. A machine of the character described comprising a frame, a feed table carried by said frame, means for moving display signs across said table longitudinally thereof, a pair of shafts carried by said frame, a plurality of platforms supported on said shafts and movable along said shafts transversely of said feed table, a tape affixing means mounted on said frame, mechanism carried by each of said platforms for supporting a roll of hinged tape and for unwinding the tape from the roll and feeding the same to said tape affixing rollers and including means for applying an adhesive to the tape as it is being unwound.
- 25 4. In testimony whereof, I hereunto affix my signature.
- 30 EDGAR W. REUTENER.
